APPARATUS FOR PRESSING GARMENT
SLEEVES

Sander Steinberg, Altoona, Pa., assignor to said Steinberg and Chester A. Miller, copartners, doing business as Altoona Sanitary Laundry, Altoona, Pa.

Application May 15, 1941, Serial No. 393,576

4 Claims. (Cl. 38—12)

My invention relates to improvements in apparatus for pressing garment sleeves.

Various types of pressing machines are known in the art. One of said types of pressing machines comprises a so-called platen presser wherein the garment is laid on a stationary buck platen and a pressing head platen is moved substantially at right angles towards said garment and buck to apply thrust pressure thereto only without any relative lateral movement whatsoever between said platens. Another class of pressing machines has comprised roller presses wherein the pressing head is of the general configuration of the roller and has been held in a stationary position abutting the pressing roller while the pressing roller itself has been rotated by hand or by machinery. Great difficulty has been experienced in providing a machine which will press garment sleeves. The roll type of presser machine is absolutely useless for this purpose, for due to its inherent nature, it provides a lateral pressure as well as a thrust pressure in exactly similar fashion to a flat iron, which is moved laterally over as well as pressed down upon the garment. Garment sleeves are usually provided with gussets adjacent the cuffs and quite often with buttons and pleats. Where one member moves laterally in close proximity to another it tends to tear the gussets, rip open the pleats and shear off the buttons. Attempts have been made to press garment sleeves on a platen presser and various forms of stationary bucks and cooperating heads have been provided for this purpose. The great difficulty with a platen presser of this description has been that each application of the pressing head presses the garment sleeve against the buck and time must be consumed in freeing the pressed garment sleeve from the buck before another application of the thrust pressure inherent in this type of a press, thus slowing down production.

An object of my invention is to employ the advantages of a platen press to apply thrust pressure only to the garment sleeve and to modify a platen type of press so that the work may be readily moved out of the way of the pressing head to make possible quick applications of thrust pressure when the pressed portion of the sleeve may be removed from a portion of a buck while another portion of the sleeve is being pressed against another portion of the buck and for this purpose I have provided a buck platen movable only for rotation substantially in the same plane that the pressing head platen is only movable in and I construct the rotatable buck of substan-

ti ally the configuration of at least a portion of said garment sleeve and suitably modify the pressing head so that thrust pressure only will be applied against such portion of a garment sleeve as the pressing head is brought into pressing juxtaposition against in a direction substantially at right angles to the garment sleeve covering the buck platen.

A further feature of my invention is to provide 10 in combination with such a modified rotatable buck in a pressing machine of the platen type of suitable stripping means so that as the buck is partially rotated for subsequent applications of thrust pressure by the pressing head, the work 15 will be automatically stripped from the buck.

A further object of my invention is to provide 20 a device which will positively not tear the gussets or buttons and upset the pleats in the garment sleeve being pressed as true radial thrust contact only is provided and no sliding contact is provided, as would be provided with a flat iron or 25 pressing machine of the roller type.

A further object of my invention is to provide 30 a novel method of pressing garment sleeves solely with radial thrust pressure so as to totally eliminate any sliding contact whatsoever of the pressure applying member over the sleeve.

These and such other objects of my invention 35 as may hereinafter appear will be best understood from a description of an embodiment thereof shown in the accompanying drawings.

In the drawings,

Fig. 1 is a front elevation of a pressing machine 35 of the platen type constructed in accordance with my invention with the pressing head in a raised open position.

Fig. 2 is an end elevation of the pressing machine shown in Fig. 1 looking towards the free end of the rotatable buck.

Fig. 3 is a front elevation similar to Fig. 1 with the pressing head moved to a closed pressing position.

Fig. 4 is a vertical sectional view taken through the modified type of rotatable buck I preferably 45 employ.

Fig. 5 is a perspective view of the perforate rotatable sleeve buck platen I preferably employ.

Figs. 6-15 are diagrammatic views illustrating 50 my improved method of pressing the entire periphery of a garment sleeve, Fig. 6 being a diagrammatic end elevation of the rotatable buck with the garment sleeve laid thereon and with the pressing head raised, Fig. 7 being a diagrammatic end elevation of the parts shown in Fig. 6 with the pressing head brought into closed pressing

position and applying thrust pressure only to a portion of the garment sleeve, and Fig. 8 being a diagrammatic end elevation similar to Fig. 1, but showing how the rotatable pressing buck may be rotated substantially one-third of its periphery for the next application of thrust pressure to a second third thereof and during such rotation causing a positive stripping of the pressed third of the sleeve from the pressing head as shown in Fig. 9; Figs. 9, 10 and 11 being identical diagrammatic end elevations respectively to Figs. 6, 7 and 8 respectively showing the sequence of steps necessary to press the second third of the garment sleeve, strip it from the rotatable buck and rotate the buck to the position shown in Fig. 12 for the application of thrust pressure to the remaining third of the sleeve; Figs. 12-14 being identical diagrammatic end elevations similar to Figs. 6, 7 and 8 and Figs. 9, 10 and 11 respectively showing the sequence of steps necessary to press the last third of the garment sleeve and strip it from the rotatable buck; and Fig. 15 being a perspective view showing how the pressed and stripped sleeve and adjacent shirt portion may be axially removed from the rotatable buck after the sequence of steps diagrammatically illustrated in Figs. 6-14 have been performed thereon.

In the drawings, wherein like characters of reference indicate like parts throughout, 20 generally indicates a garment sleeve to be pressed and preferably additionally stripped by my improved method. Employing my improved method I am enabled through the application of a thrust pressure only substantially at right angles to the axis of the sleeve to press the garment without the application of lateral tearing pressure to the gusset 21 thereof, or buttons or pleats which are often present on garment sleeves. No method has been hitherto provided for pressing garment sleeves in a satisfactory manner. Even employing a flat iron the sleeves have had to be laid flat on the ironing board, or on a suitable form and it has been substantially impossible to apply a true radial thrust pressure to the axis of the garment sleeve for no matter what care has been taken the iron has always slid over the surface of the sleeve, nor have flat irons been of sufficient weight to apply sufficient pressure over buttons or pleats to iron them in a satisfactory manner. In accordance with my method I axially pull the garment sleeve 20 over a rotatable member 22 having a periphery 24 of the general configuration of a garment sleeve and if it be desired to simultaneously strip the garment sleeve from said rotatable member, a rotatable member having a periphery of the general configuration of a portion only of said garment sleeve and a stripping finger 26 extending parallel thereto at a spaced distance 28 therefrom are provided, the garment sleeve thus being axially pulled over a portion of the periphery of the rotatable member 22 and the stripping finger 26 during the initial lay of the garment sleeve on the rotatable member. The gussets, pleats, or buttons may thus be definitely laid in a flat position on the periphery of the rotatable member, but if desired a portion of the periphery of the garment sleeve free of such irregularities may be initially laid on the rotatable member for the application of thrust pressure thereto.

I have shown in the drawings a sleeve 20 having a cuff 30 attached thereto with the gusset 21 extending through said cuff and a substantial distance axially of the end of the sleeve. It is obvious, however, that certain types of sleeves

do not have gussets. I then apply thrust pressure in a single plane substantially at right angles to said garment sleeve 20 and rotatable member 22 only to a portion 32 of said garment sleeve overlying a portion 34 of said rotatable member 22. In the improved method shown this is accomplished by moving the pressing head 36 having a concave pressing surface 38 of substantially the configuration of the portion 34 of the buck platen 22 against which it abuts in a single plane against the portion 32 of the garment sleeve and 34 of the rotatable member as shown in Fig. 7. After thrust pressure has been applied to the portion 32, in the embodiment shown, comprising substantially one-third of the sleeve to smooth or flatten it as shown at 49 in Figs. 7 and 8, the rotatable member 22 may be positively partially rotated by the hand 42 or in any other suitable manner to bring another portion 44 of the sleeve, in the embodiment shown, another third 44 of the periphery of the garment sleeve in juxtaposition over the portion 46 of the rotatable member for a subsequent application of thrust pressure only thereto by again pressing down the pressing head 36 in juxtaposition against the portion 44 of the sleeve in the manner shown in Fig. 10. Where the stripping finger 26 is employed the pressed portion or third 32 of the garment sleeve 20 will be rotated by the hand 42 to the position shown in Fig. 9 stripping said portion 32 from the adjacent portion 34 of the rotatable member 22.

Figs. 9-12 illustrate how the next portion or third 44 of the sleeve 22 is similarly pressed against the portion or third 46 of the rotatable member and similarly stripped therefrom.

Figs. 11-14 illustrate how the last third 48 of the garment sleeve 22 overlying the last third 50 of the rotatable member 22 is similarly pressed and stripped therefrom.

It is thus obvious that the applications of thrust pressure and intermediate positive partial rotations of said rotatable member and garment sleeve are repeated, in the embodiment shown, three times until said rotatable member 22 is completely rotated and said garment sleeve 20 completely pressed with thrust pressure only and with no relative sliding contact of the pressing members thereover and stripped from said rotatable member 22.

As shown in Fig. 15 the completely pressed sleeve 20 and adjacent shirt portion 52 may be axially removed from said rotatable member 22 and stripping finger 26 by pulling it axially out over the free end 54 of said rotatable member 22.

While my improved method may be performed by hand or automatically by any suitable mechanism, I have discovered that it may be accurately performed by a modified type of platen press, particularly a platen press 56 of standard type in which the pressing head 36 is mounted on the end of a pressing lever 58 pivotally mounted on an extension 60 projecting upwardly from the frame 64 in rear of the table 62 and in which the usual buck 22 is modified into the rotatable member 22, although any type of a press for applying the pressure thrust of a presser head platen movable in a single plane substantially at right angles to a portion of the garment sleeve 20 covering a buck platen 22 movable only for rotation substantially in the plane of the movement of the pressing head may be employed. Said pressing machine 56 of the movable platen type comprises the usual frame 64 on which

the table 62 and projection 60 are mounted as usual.

To mount the buck platen 22 above said table I provide a support 72 projecting upwardly from adjacent one end only of said table having an axle portion 74 extending longitudinally over said table 62 substantially parallel thereto. While the axle portion 74 may be of any suitable configuration to have the rotatable member or buck platen 22 rotatably mounted thereon, I preferably so construct my rotatable member 22 that it will immediately stop its rotation and assume a set position immediately on release of rotating torque thereon so that its set position may be immediately attained for the application of thrust pressure solely thereto by the depression of the pressing head 36. For this purpose the axle portion 74 is preferably constructed of frusto-conical shape, tapering outwardly as at 76 and the rotatable buck platen 22 is preferably mounted as a sleeve 22 to rotate on said axle portion 74. As means for supporting said sleeve 22 on said axle portion 74 I provide annular bearing means on the periphery of said axle portion, preferably comprising a plurality of axially spaced annular bearings, in my preferred embodiment shown, one annular bearing 78 being located at the inner end thereof, another 80 being located substantially centrally thereof and a third 82 located at the outer end thereof. It is obvious that any number of such annular bearings may be employed, preferably two axially spaced annular bearings so as to rotatably support the rotatable member 22 on said axle 74 without any tilting movement. The axle portion 74 is preferably constructed hollow so as to provide the central chamber 84 thereof as a heating chamber and suitable means such as the inlet pipe 86 may be provided for inserting live steam within said heating chamber 84 and suitable means such as the outlet pipe 88 may be provided for drawing condensed water therefrom.

In the embodiment shown, the buck platen comprises the sleeve 22, preferably a frusto-conical sleeve 22 similarly outwardly tapered as at 90. It is thus obvious that the inner periphery of the sleeve 22 rests on and is supported by the annular bearings 78, 80 and 82. It is apparent that with this construction employing a light thin sleeve rotating on a relatively heavy enlarged axle that the rotation of the sleeve 22 will immediately stop once the application of turning torque is withdrawn from said sleeve 22. It is obvious that alternatively in case a sleeve 22, or other rotatable member is freely rotatable on its respective axle 74 that analogous means other than the structure of the actual sleeve itself such as suitable braking means may be employed for causing the immediate cessation of rotation of said sleeve 22 on said axle 74 upon the cessation of the application of turning torque thereto. This is an inherently desirable feature of my invention as distinguished from the free rotation of the rollers in roller presses which are mounted on non-friction bearings to rotate freely after the application of turning torque to lessen the amount of power required for their rotation. The sleeve 22 may be perforated if desired as shown at 92 and a suitable preferably pervious resilient covering for said platen buck may be provided, such as the outer felt covering 94. With the axle 74 and pressing buck 22 rotatable thereon mounted on the single support 72 projecting upwardly from said frame, it is obvious that both the axle

14 and sleeve 22 will each have a free end over which the garment sleeve 20 may be readily drawn and withdrawn in the manner indicated in Fig. 15, with the cuff 30 on the free end of the garment sleeve overlying the free end 54 of the rotatable member 22. The pressing surface 38 of the pressing head 36 is preferably transversely concealed and is of substantially the configuration of the portion of said buck platen 22 immediately underlying it and is preferably similarly outwardly tapered as at 37 to the periphery of the rotatable buck platen 22, and on raising of the power arm of the pressing lever 58 is movable only in a single plane substantially at right angles towards said buck platen 22.

Suitable means are provided to move said pressing head platen 36 towards said buck platen 22 in said single plane only to apply thrust pressure only against a then stationary portion of the garment sleeve 20 mounted on the then stationary buck platen 22, such as the respective third portions 32, 44 and 48 of the garment sleeve overlying the respective third portions 34, 46 and 50 of the buck and to reversely draw said pressing head platen 36 away from said buck platen 22. While any suitable means may be provided for this purpose, power actuated or otherwise, I have shown in the drawings a foot treadle 96 operating suitable linkage, including the bell crank toggle 98 and lever toggle 100 to raise the power arm of said pressing lever 58 on depression of said foot treadle 96 to pivot the pressing head 36 into pressing juxtaposition with the garment sleeve 20 and rotatable buck platen 22, and conversely to permit lowering of the pressing lever by the weight of the power arm 102 when pressure is removed from the foot treadle 96 and consequent raising of the pressing head 36 away from said buck platen 22.

As stated hitherto, a great difficulty with the use of presses of the platen type in pressing garment sleeves has been the loss of time required in removing the pressed portion of the sleeve from the buck 22 after the application of ironing pressure thereto. It is obvious that employing my improved rotatable buck that after each lowering of the pressing head 36, during subsequent raising thereof, the rotatable member 22 and attached garment sleeve 20 may be quickly rotated to bring a non-pressed portion of the garment sleeve into position immediately below the head so that the pressing head 36 may be immediately lowered to press a further portion of the garment sleeve immediately after its first pressing operation.

Employing my improved method and pressing machine, I am additionally enabled to provide therewith a novel method of automatically stripping the pressed portions of the garment sleeve from the rotatable member 22 as the rotatable member 22 with the garment sleeve mounted thereon is being positively partially rotated to bring the adjacent unpressed portion of the garment sleeve into position immediately below the pressing head 36 for its immediate subsequent pressing by thrust pressure and for this purpose I provide suitable stripping means, such as the stripping finger 26 hitherto described, rigidly mounted on said press to extend adjacent and parallel to said buck platen at a closely spaced distance 38 therefrom. I employ the word "stripping finger" in the claims as significant of its function regardless of the particular mechanical shape the stripping means may assume. In the preferred embodiment shown, the stripping finger

26 comprises the wire rod 26 having its outer end 104 bent at right angles upwardly and provided with a loop 106 for surrounding the stud 108 projecting axially from the free outer end of the axle 74. If desired, a disc 110 may be first inserted on said bolt and may be of a radial length as shown, to abut the outer edge of the rotatable sleeve 22 to retain it in position against axial movement on said annular bearings 78, 80 and 82. After the disc 110 and loop 106 are mounted on said stud 108 the nut 112 may be tightened on said stud 108 and if a braking action is desired it may be tightened in such a manner as to cause the inner surface of said disc to continuously abut the outer edge of said rotatable sleeve 22 to cause it to stop rotation immediately on the cessation of application of turning torque thereto in the event that the rotatable member 22 and axle 74 be constructed other than of the outwardly tapered frusto-conical shapes shown, with the sleeve 22 of a light construction relative to the axle 74.

It is thus apparent that with this construction said buck platen 22 and garment sleeve 20 may be retained in a stationary position during the application of thrust pressure and that said rotatable buck platen 22 and garment sleeve 20 may be successively positively partially rotated in the manner hitherto explained to a plurality of set thrust pressure applying positions with the stripping finger 26 positively stripping the pressed portions of said sleeve from said buck platen during such rotation thereof between intermittent applications of thrust pressure by said pressure head platen 36 until said buck platen 22 is completely rotated and said garment sleeve 20 completely pressed and if the stripping finger 26 be employed, the pressed garment sleeve 20 being also stripped from said buck platen 22.

It is apparent that I have provided a novel method of pressing a garment sleeve which may be accomplished by hand or by a novel method of manipulation of a modified type of platen press, or other mechanisms to completely press any type of a sleeve without damaging any part thereof in a novel satisfactory manner with the advantages described above.

It is understood that my invention is not limited to the specific embodiments shown and that various deviations may be made therefrom without departing from the spirit and scope of the appended claims.

What I claim is:

1. In a press for applying the pressure thrust of a pressing head platen movable only in a single plane substantially at right angles to a portion of a garment sleeve covering a buck platen movable only for rotation substantially in the same plane, a frame, a support projecting from one portion only of said frame having a hollow outwardly tapered frusto-conical axle portion having axially spaced annular bearings on the periphery thereof between the ends and at the ends thereof, a buck platen comprising an outwardly tapered frusto-conical perforate sleeve having a periphery of the general configuration of a portion only of a garment sleeve mounted for rotation on said axle portion bearings, the frictional characteristics of said bearing being such that said buck platen will remain in a set position on release of rotating torque thereon for the application of thrust pressure thereto, a pervious resilient covering for said buck platen and a stripping finger rigidly mounted on said press to extend adjacent and parallel to said buck platen at a closely spaced distance therefrom so that a garment

sleeve may be pulled over said buck platen and stripping finger from the free ends thereof to have the free end thereof rest over the free end of said buck platen, a pressing head platen having a concave pressing surface of substantially the configuration of a portion of said buck platen and similarly outwardly tapered to the periphery of the rotatable buck platen movable only in a single plane substantially at right angles to said buck platen and means to move said pressing head platen towards said buck platen in said single plane only to apply thrust pressure only against a then stationary portion of said garment sleeve mounted on the then stationary buck platen and away from said buck platen, whereby said buck platen and garment sleeve may be retained in a stationary position during the application of thrust pressure and said rotatable buck platen and garment sleeve may be successively positively partially rotated to a plurality of set thrust pressure applying positions with the stripping finger positively stripping the pressed portion of said sleeve from said buck platen during such rotation between intermittent applications of thrust pressure by said pressing head platen until said buck platen is completely rotated and said garment sleeve completely pressed and stripped from said buck platen and means to insert live steam within said hollow axle.

2. In a press for applying the pressure thrust of a pressing head platen movable only in a single plane substantially at right angles to a portion of a garment sleeve covering a buck platen movable only for rotation substantially in the same plane, a frame, a support projecting from one portion only of said frame having an axle portion, a buck platen having a periphery of the general configuration of a portion only of a garment sleeve mounted for rotation on said axle portion, and a stripping finger in the form of a substantially rigid rod rigidly mounted on said press to extend adjacent and parallel to said buck platen at a closely spaced distance therefrom so that a garment sleeve may be pulled over said buck platen and stripping finger from the free ends thereof to have the free end thereof rest over the free end of said buck platen, a pressing head platen having a concave pressing surface of substantially the configuration of a portion of said buck platen movable only in a single plane substantially at right angles to said buck platen and means to move said pressing head platen towards said buck platen in said single plane only to apply thrust pressure only against a then stationary portion of said garment sleeve mounted on the then stationary buck platen and away from said buck platen, whereby said rotatable buck platen and garment sleeve may be successively positively partially rotated to a plurality of set thrust pressure applying positions with the stripping finger positively stripping the pressed portion of said sleeve from said buck platen during such rotation between intermittent applications of thrust pressure by said pressing head platen until said buck platen is completely rotated and said garment sleeve completely pressed and stripped from said buck platen.

3. In a press for applying the pressure thrust of a pressing head platen movable only in a single plane substantially at right angles to a portion of a garment sleeve covering a buck platen movable only for rotation substantially in the same plane, a frame, a support projecting from one portion only of said frame having an axle portion, a buck platen having a periphery

of the general configuration of a portion only of a garment sleeve mounted for rotation on said axle portion, the frictional engagement of said buck platen with said axle portion being such that the buck platen will remain in a set position on release of rotating torque thereon for the application of thrust pressure thereto, and a stripping finger in the form of a substantially rigid rod rigidly mounted on said press to extend adjacent and parallel to said buck platen at a closely spaced distance therefrom so that a garment sleeve may be pulled over said buck platen and stripping finger from the free ends thereof to have the free end thereof rest over the free end of said buck platen, a pressing head platen having a concave pressing surface of substantially the configuration of a portion of said buck platen movable only in a single plane substantially at right angles to said buck platen and means to move said pressing head platen towards said buck platen in said single plane only to apply thrust pressure only against a then stationary portion of said garment sleeve mounted on the then stationary buck platen and away from said buck platen, whereby said buck platen and garment sleeve may be retained in a stationary position during the application of thrust pressure and said rotatable buck platen and garment sleeve may be successively positively partially rotated to a plurality of set thrust pressure applying positions with the stripping finger positively stripping the pressed portion of said sleeve from said buck platen during such rotation between intermittent applications of thrust pressure by said pressing head platen until said buck platen is completely rotated and said garment sleeve completely pressed and stripped from said buck platen.

4. In a press for applying the pressure thrust of a pressing head platen movable only in a single plane substantially at right angles to a portion

- of a garment sleeve covering a buck platen movable only for rotation substantially in the same plane, a frame, a support projecting from one portion only of said frame having an axle portion having axially spaced annular bearings on the periphery thereof between the ends and at the ends thereof, a buck platen comprising a sleeve having a periphery of the general configuration of a garment sleeve mounted for rotation on said axle portion bearings, the frictional characteristics of said bearing being such that said buck platen will remain in a set position on release of rotating torque thereon for the application of thrust pressure thereto so that a garment sleeve may be pulled over said buck platen from the free end thereof to have the free end thereof rest over the free end of said buck platen, a pressing head platen having a concave pressing surface of substantially the configuration of a portion of said buck platen and similarly outwardly tapered to the periphery of the rotatable buck platen movable only in a single plane substantially at right angles to said buck platen and means to move said pressing head platen towards said buck platen in said single plane only to apply thrust pressure only against a then stationary portion of said garment sleeve mounted on the then stationary buck platen and away from said buck platen, whereby said buck platen and garment sleeve may be retained in a stationary position during the application of thrust pressure and said rotatable buck platen and garment sleeve may be successively positively partially rotated to a plurality of said thrust pressure applying positions between intermittent applications of thrust pressure by said pressing head platen until said buck platen is completely rotated and said garment sleeve completely pressed.

40

SANDER STEINBERG.
